CLAIM

The ornamental design for a water hose, as shown and described.

DESCRIPTION

FIG. 1 is a perspective view of a water hose showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The water hose is shown with a symbolic break in its length and the appearance of any portion of the water hose between the break lines form no part of the claimed design. The broken lines in the drawings depict portions of the water hose that form no part of the claimed design.
